WEDGE-BLOCK BREECH MECHANISM.

1,072,456.

Specification of Letters Patent.

Patented Sept. 9, 1913.

Application filed December 2, 1911. Serial No. 663,575.

To all whom it may concern:

Be it known that I, MAX HERMSDORF, a subject of the Emperor of Germany, and a resident of Essen-on-the-Ruhr, Germany, 5 have invented certain new and useful Improvements in Wedge-Block Breech Mechanisms, of which the following is a specification.

The present invention relates to breech 10 mechanisms for guns, particularly to such mechanisms that have a wedge block operated by a cam lever that, in opening the mechanism, cocks the firing lock by means of a cocking member, and the invention relates principally therein, that said cocking member constitutes a pivot for a lever that is adapted to cock the firing lock on misfire.

One embodiment of the invention is represented on the drawing in a gun with a horizontal wedge block, and Figure 1 shows a horizontal length section of the breech end of the gun barrel with the wedge block in full lines and in the closed position of the mechanism and with pulled off firing lock. Fig. 25 2 a horizontal section of the wedge block in the same position as in Fig. 1; Fig. 3 a rear view of the breech and the wedge block partly in section with the parts in the same position as in Fig. 1; Fig. 4 a sectional view 30 corresponding to Fig. 1, but with the wedge mechanism partly open; Fig. 5 also a similar view to Fig. 1 but with the mechanism represented in almost closed position; Fig. 6 a section on line 6—6 of Fig. 4 and Fig. 7 35 a horizontal section of the breech and wedge block with the firing lock cocked.

The wedge block B guided in the breech end A of the gun barrel is adapted to be moved by means of the cam lever C, Figs. 40 1, 3, 4 and 5. This cam lever is pivoted in the breech end A and provided with a heart shaped cam lug c¹ engaging a cam groove b¹ in the upper face of the wedge block B. Within the wedge block B is mounted a firing pin D actuated by a firing spring E and a two armed cocking lever F by means of which the firing pin will be transferred from the pulled off position shown in Figs. 1 and 2, into the cocked position represented 45 in Figs. 4, 5, 6 and 7. A pawl G adapted to retain the firing pin in its cocked position is firmly connected with the trigger bolt H, see Figs. 6 and 7, rotatively carried in the wedge block and provided with a trigger H¹.

When the firing pin is in the cocked position, the pawl G engages by means of a tooth g¹, a cut d¹ provided on the firing pin, see Fig. 6. The firing spring E rests at one end against the bottom of the counter bore 60 of the firing pin D and with its other end against an arm g², see Fig. 6 of the pawl G.

The cam lever C has on its bottom side an approximately triangular recess c², Figs. 1 and 3, the walls c³ and c⁴ of which run eccentrically to the axis of rotation of the cam lever, Figs. 1, 4 and 5. The wall c³ of the recess c² is intended to coöperate with a finger k¹ eccentrically located on a bolt K, Figs. 1, 2, 3, 4 and 5, when the breech mechanism is opened; while the wall c⁴ coöperates with the said finger k¹ toward the end of the closing movement of the cam lever. The bolt K is vertically mounted in the wedge block B and is provided at its lower end with the flat cut k², one edge k³ of which is constructed to coöperate with a beveled face f¹ of the cocking lever F in the direction of the cocking of the firing pin, when the bolt K is turned in the opposite direction to the 70 hands of the clock from the position shown in Figs. 1 and 2.

On a pivot k⁴ provided at the lower end of the bolt K, see Figs. 3 and 7, a lever R is mounted. This lever is provided with a toe r¹, Fig. 7, which also is adapted to coöperate with the bevel face f¹ of the cocking lever F and to cause the cocking of the firing pin when the lever R is turned from the position shown in Figs. 1, 2, 3, 4 and 5 into 80 the position shown in Fig. 7. A helical spring M, Figs. 2 and 7, inserted with initial tension between the toe f² of the cocking lever F on one side and by means of a plunger m¹ bears against the toe r² of the lever R on the other side. The spring M endeavors to hold the cocking lever F and the lever R in the position corresponding to the uncocked position of the firing lock, illustrated in Fig. 2.

A filling piece N, see Fig. 3, is inserted in a rectangular recess b² of the wedge block B having a shape closely adhering to that of the recess b². The filling piece N is held in place by means of the pivot k⁴ of the bolt K which reaches through a hole in the filling piece into the lower wall of the recess b². On a pivot pin n¹ situated on top of the filling piece N the cocking lever F is mounted. The spring M and the pin n¹ are carried in 100 105 110

a housing n^2 which is in one piece with the filling piece N.

When the breech mechanism is opened, the firing lock is transferred into the cocked position by means of the bolt K, in which position it is retained by the pawl G, Figs. 4 and 6. When the mechanism is closed again the wall c^4 of the recess c^2 strikes against the finger k^1 toward the end of the closing movement, so that during the last part of the closing movement of the cam lever, the bolt K will be returned into its initial position. The cocking lever F also returns, actuated by the spring M into its initial position.

To fire the gun, the trigger H^1 is pulled, whereby the toe g^1 of the pawl G retires out of engagement with the cut d^1 of the firing pin D.

In case of misfire, the lever R is brought out from its normal position into the position shown in Fig. 7. The toe r^1 of the lever R slides then along the bevel face f^1 of the cocking lever F, so that hereby the firing lock is recocked and may be pulled off again. After the cocking of the firing lock the cocking lever F and the lever R return to their original positions under the action of the spring M.

I claim:—

1. In a wedge block mechanism for guns, the combination with an operating lever and a firing lock; of a cocking arm for said firing lock; a cocking bolt revolved by the opening of the mechanism and actuating said cocking arm; a hand lever, rotatably mounted on said cocking bolt and adapted to coöperate with said arm for cocking the firing lock.

2. In a wedge block mechanism for guns, the combination with an operating lever and a firing lock; of a cocking arm for said firing lock; a cocking bolt revolved by the

opening of the mechanism and actuating said cocking arm; a detachable seat, locked in position by means of said cocking bolt; a pivot pin on said seat; said cocking arm being mounted to oscillate around said pivot pin.

3. In a wedge block mechanism for guns, the combination with an operating lever and a firing lock; of a cocking arm for said firing lock; a cocking bolt revolved by the opening of the mechanism and actuating said cocking arm; a hand lever, rotatably mounted on said cocking bolt and adapted to coöperate with said arm for cocking the firing lock; means for holding said hand lever and said cocking arm in their normal positions comprising a toe on said hand lever, a finger on said cocking arm, a spring and a spring plunger.

4. In a wedge block mechanism for guns, the combination with an operating lever and a firing lock; of a cocking arm for said firing lock; a cocking bolt revolved by the opening of the mechanism and actuating said cocking arm; a hand lever, rotatably mounted on said cocking bolt and adapted to coöperate with said arm for cocking the firing lock; means for holding said hand lever and said cocking arm in their normal positions comprising a toe on said hand lever, a finger on said cocking arm, a spring and a spring plunger; a detachable seat, locked in position by means of said cocking bolt; a pivot pin on said seat, said cocking arm being mounted to oscillate around said pivot pin.

The foregoing specification signed at Bar-
men, Germany, this 11th day of November,
1911.

MAX HERMSDORF. [L. S.]
